UNITED STATES PATENT OFFICE

ALEXANDRE DAUVILLIER, OF PARIS, FRANCE

PROCESS AND APPARATUS OF RADIOSCOPY, RADIOPHOTOGRAPHY, AND RADIOCINEMATOGRAPHY

Application filed January 31, 1928, Serial No. 250,942, and in France February 2, 1927.

The present invention is adapted to obviate the inconveniences presented, heretofore, by the known processes and apparatus of radio-diagnosis, which are: the danger due to X rays, the small luminosity of radioscopic images, the limitation of the field of investigation of these processes, and the blurring due to secondary radiation.

The invention consists in receiving the radiologic shadow, no longer on a luminescent screen or a radiographic film as heretofore, but on a single large radioelectric detector, such as an ionization chamber or a surface of selenium, by exploring the field of radiation by means of a suitable movable diaphragm, selecting therein at every instant, without loss of time, a slender beam of X rays, of invariable size. The corresponding electric current, issued from the radiodetector, is suitably amplified and modulates the instantaneous luminosity of a source of light without inertia, such as a discharge lamp, or a light valve of the Kerr's type for instance. This source illuminates a movable diaphragm receiving synchronous movements in phase with those of the analyzing diaphragm owing to a mechanical connection. The latter appears as a continuous and animated image as soon as the exploration and synthesis are repeated at least ten times per second.

The accompanying drawings illustrate, by way of example, two forms of carrying the invention into practice.

Fig. 1 shows a diagrammatic view of the first form; Fig. 2 represents the movable diaphragm; Fig. 3 shows a fragmentary diagrammatic view of the second form.

The X-ray tube 1 illuminates the subject 2 through the fixed diaphragm 3 and the movable diaphragm 4 which allows the passage, through the orifice 5, of the slender beam 6. The latter strikes upon the radioelectric detector 7 which is here, for example, an ionization chamber. This chamber is composed of a box 7 of conducting material brought to a high continuous potential by the source of potential 8. It is provided with a partition or cover 9 through which can pass the X rays. One or more inner insulated electrodes 10 protected by a guard ring 11 collect the ions

formed along the beam 6. These electrodes are covered with a deposit, of lead for instance, obtained by the Schoop's process or any other process, increasing their electronic emission. The chamber may contain a heavy, compressed and dried gas. The tension applied can be sufficiently high for producing the ionization by shock. The current produced flows through an ohmic resistance or a kenotron 12 and the difference of potential produced is applied on any usual amplifier, which may be a direct current vacuum tube amplifier, the modulation grid of which is electrostatically protected and the stages of which are connected by resistances and counter-batteries. The difference of potential 13 is applied to the terminals of a multiple Kerr condenser 14 arranged between a polarizing nicol and an analyzing nicol which are crossed. The light issues from a lamp 17 arranged at the focus of an optical condenser 18. The parallel light beam modulated by the difference of potential 13 passes through the orifice 19 diametrically opposite the orifice 5. It is received by the objective 20 and projected at 21 upon the screen 22.

Fig. 2 shows a diaphragm for analyzing the radiologic shadow on one hand and for reconstituting the optical image on the other hand. It is a disc opaque to X rays and to light, perforated with two symmetrical diametrically opposite Nipkow spirals. The first one has n holes (1 to n) closed for instance by means of black paper. The second one has also n holes (1' to n') closed by plugs made of glass containing lead, which can also consist of large lenses replacing the objective 20. This disc is moved by the motor 26 at the minimum speed of 600 revolutions per minute (10 complete images per second) in the case of radioscopy and of radiocinematography.

The form of carrying the invention into practice as shown in Fig. 1 is more particularly adapted for being used for radioscopy. On the contrary, the form shown by Fig. 3 is intended to be used for radiography and radiocinematography. The said form differs from the first in that the screen 22 is eliminated and replaced by a film 23 supported by the reels 24 and 25.

For obtaining radiography, the film 23 is immobilized in the neighborhood of the diaphragm 4 or arranged in the image plane of the objective 20. For obtaining cinema, this film is unwound by the reels 24 and 25 driven by the motor 26, so as to be immobilized during each complete rotation and rapidly displaced to the extent of one image at each revolution.

- 10 As shown in the fragmentary diagram, Fig. 3, this is accomplished by well known means comprising a Geneva gear *a* driven by the finger or tooth *b* of the drum *c*, mounted on the shaft of the motor 26. The Geneva gear *a* drives the drum 24 by means of wheels *d* and *e*, connected by the chain or belt *f*. Such devices are common and well known in cinematographic apparatus.

15 The diaphragm illustrated in the figures 20 can obviously be replaced by any other equivalent system of simple or multiple diaphragms, perforated with holes or rectilinear or curvilinear slots, receiving rotary, oscillating or translation movements, analyzing 25 the image according to any trajectory, with uniform or variable speed of exploration, whilst remaining within the scope of the invention.

20 What I claim as my invention and desire to 30 secure by Letters Patent is:—

1. In a radiologic process the steps which 35 consist in producing a slender beam of X rays; in exploring a subject by means of the said slender beam, in using the said slender beam after passing through the said subject 40 for modulating an electric current in using the said electric current for modulating the instantaneous luminosity of a source of light, in selecting a beam of the said source of light, and imparting to the said beam synchronous 45 movements in phase with those of the slender beam of X rays.

2. Apparatus for carrying out the process 45 as claimed in claim 1, which comprises in combination a source of X rays, means for selecting at every instant a slender beam of X rays the size of which is invariable, means for exploring a subject by the said slender beam and selecting a beam of light, a radioelectric 50 detector for receiving the said slender beam after passing through the said subject, and for transforming the variations thereof into electrical variations, a source of light, means for modulating the instantaneous 55 luminosity of the said source of light according to the said electrical variations, said means for selecting a beam of light, also imparting to the same synchronous movements in phase with those of the slender beam of 60 X rays, and a screen for receiving the beam of light.

3. Apparatus for carrying out the process 65 as claimed in claim 1, which comprises in combination a source of X rays, a source of light, a movable diaphragm adapted to select,

at every instant, a slender beam of X rays the size of which is invariable, to explore a subject by the said slender beam, to select a beam of light, and to impart to the same synchronous movements in phase with those of the slender beam of X rays, a radioelectric detector for receiving the said slender beam after passing through the said subject, and for transforming the variations of said beam into electrical variations, means for modulating the instantaneous luminosity of the said source of light according to the said electrical variations, and a screen for receiving the beam of light.

70 In testimony whereof I have signed my 80 name to this specification.

ALEXANDRE DAUVILLIER.
